UNITED STATES PATENT OFFICE

PAUL LOUIS GASTON ALBERT, OF AULNAY-SOUS-BOIS, FRANCE, ASSIGNOR TO THE BAB-COCK & WILCOX COMPANY, OF BAYONNE, NEW JERSEY, A CORPORATION OF NEW JERSEY

FLUID HEATER

Application filed June 16, 1921, Serial No. 477,876, and in France October 1, 1920.

My invention relates to improvements in fluid heaters in which the fluid passes through tubes connected to headers. In the illustrative form, the tubes 15, 16, which are preferably unjointed as illustrated, are treated as a group and are provided such a fluid heater in which any one of the tubes connecting the headers can be readily removed and replaced without disturbing the other parts.

One of the objects of my invention is to provide such a fluid heater in which any one of the tubes connecting the headers can be readily removed and replaced without disturbing the other parts. Another object of my invention is to provide such a heater so that the fluid will pass therethrough in such a manner as to give efficiency in operation, and so that, at the same time, the headers and the tubes may be readily accessible.

With these and other objects in view, my invention consists of the constructions and arrangements hereinafter described and specifically pointed out in the appended claims.

In the drawings: Figure 1 is an end elevation of one form of fluid heater embodying my invention; Fig. 2 is a section on the lines A—B—C—D, looking from the right of Fig. 4; Fig. 3 is a vertical section on the lines E—F—G—H of Fig. 4; and Fig. 4 is a horizontal section on the lines I—J—K—L of Fig. 3.

Like reference characters indicate like parts in the several views.

For purposes of illustration, I have selected an economizer in which water may be heated by the waste flue gases of a steam boiler; but it will be understood that my invention may also be applied to other forms of fluid heaters, such as superheaters.

In the illustrative form, I have shown such a heater in multiple, but a description of a single heater will be sufficient for an understanding of the invention. In the illustrative form, each heater has a plurality of

vertical headers 10, 11, 12 and 13, the lower ends of which may be conveniently supported on bases 14. These headers are parallel and are divided into pairs, as shown best in Fig. 4.

While I have selected a header which is square in cross-section as my preferred form, it will be understood that any other suitable cross-section may be used.

Connecting each pair of headers is a plurality of bent tubes, each tube lying in

plane at right-angles to the axes of the headers. In the illustrative form, the tubes 15, 16, which are preferably unjointed as illustrated, are treated as a group and are provided such a fluid heater in which any one of the tubes connecting the headers can be readily removed and replaced without disturbing the other parts. Another object of my invention is to provide such a heater so that the fluid will pass therethrough in such a manner as to give efficiency in operation, and so that, at the same time, the headers and the tubes may be readily accessible.

With these and other objects in view, my invention consists of the constructions and arrangements hereinafter described and specifically pointed out in the appended claims.

In the drawings: Figure 1 is an end elevation of one form of fluid heater embodying my invention; Fig. 2 is a section on the lines A—B—C—D, looking from the right of Fig. 4; Fig. 3 is a vertical section on the lines E—F—G—H of Fig. 4; and Fig. 4 is a horizontal section on the lines I—J—K—L of Fig. 3.

Like reference characters indicate like parts in the several views.

For purposes of illustration, I have selected an economizer in which water may be heated by the waste flue gases of a steam boiler; but it will be understood that my invention may also be applied to other forms of fluid heaters, such as superheaters.

In the illustrative form, I have shown such a heater in multiple, but a description of a single heater will be sufficient for an understanding of the invention. In the illustrative form, each heater has a plurality of

vertical headers 10, 11, 12 and 13, the lower ends of which may be conveniently supported on bases 14. These headers are parallel and are divided into pairs, as shown best in Fig. 4.

While I have selected a header which is square in cross-section as my preferred form, it will be understood that any other suitable cross-section may be used.

Connecting each pair of headers is a plurality of bent tubes, each tube lying in

plane at right-angles to the axes of the headers. In the illustrative form, the tubes 15, 16, which are preferably unjointed as illustrated, are treated as a group and are provided such a fluid heater in which any one of the tubes connecting the headers can be readily removed and replaced without disturbing the other parts. Another object of my invention is to provide such a heater so that the fluid will pass therethrough in such a manner as to give efficiency in operation, and so that, at the same time, the headers and the tubes may be readily accessible.

With these and other objects in view, my invention consists of the constructions and arrangements hereinafter described and specifically pointed out in the appended claims.

In the drawings: Figure 1 is an end elevation of one form of fluid heater embodying my invention; Fig. 2 is a section on the lines A—B—C—D, looking from the right of Fig. 4; Fig. 3 is a vertical section on the lines E—F—G—H of Fig. 4; and Fig. 4 is a horizontal section on the lines I—J—K—L of Fig. 3.

Like reference characters indicate like parts in the several views.

For purposes of illustration, I have selected an economizer in which water may be heated by the waste flue gases of a steam boiler; but it will be understood that my invention may also be applied to other forms of fluid heaters, such as superheaters.

In the illustrative form, I have shown such a heater in multiple, but a description of a single heater will be sufficient for an understanding of the invention. In the illustrative form, each heater has a plurality of

vertical headers 10, 11, 12 and 13, the lower ends of which may be conveniently supported on bases 14. These headers are parallel and are divided into pairs, as shown best in Fig. 4.

While I have selected a header which is square in cross-section as my preferred form, it will be understood that any other suitable cross-section may be used.

Connecting each pair of headers is a plurality of bent tubes, each tube lying in

13, each flue being open at the bottom and connected across the middle partition at the top. Gases may enter the flue at the left-hand side of Fig. 2 and, following the 5 dotted line, will pass upward and then across the middle partition and then downward to the outlet at the right-hand side of Fig. 2. At the same time, the water by entering the lower part of the header 11 10 will flow generally upward through the flue at the right of Fig. 2 and generally downward through the flue at the left of Fig. 2, as shown by the full line arrows, passing from the header 11 at its upper end to the 15 upper end of the header 12 through the pipe 28. In passing up and down these flues, however, the fluid is compelled to circulate back and forth across the same by reason of the presence of the partitions in the headers, as will be readily understood by an inspection of the left-hand portion of Fig. 2.

In the form illustrated, the casing surrounding the heater is made up of plates provided with suitable insulation, and a 25 series of doors 30 are provided opposite the handholes in the headers. In addition, removable portions 31 are provided in the casing.

In operation, it will be understood that 30 the gases, by reason of their passage up and down the flues, directed also by baffles 32 which may be provided, flow across the looped or bent tubes, the flow of the gases and the flow of the water through the tubes 35 being in reverse directions, so that the counter-flow method of operation is obtained. If, for any reason, one of the tubes 15, 16 fails and is to be removed, the appropriate doors 30 and the removable part of the casing 31 opposite the damaged tube will be 40 opened or removed and the damaged tube will then be cut out. It can be removed from its position by collapsing the bent portion in the plane of the tube until the 45 width of the area covered by the tube is less than the distance between the headers, the tubes having sufficient flexibility to be withdrawn without permanent deformation. The space between the headers and the 50 length of the tubes and the manner of their bending are arranged so as to permit the legs of the tubes to be drawn in sufficiently to enable the tube to be passed between the headers without permanent deformation of 55 the bends of the tubes. Similarly, a new tube, bent to the form shown in Fig. 4, may be passed between the headers by collapsing the bends to bring the legs of the tubes 60 sufficiently close together. When thus collapsed, the tube can be passed into position between the next adjacent upper and lower tubes and without disturbing the latter and after the new tube has passed the headers, 65 the legs will be permitted to spring into

position to be entered into the proper faces of the headers.

By my construction the end portions of the legs of the tubes may be straight and not subjected to severe right-angle bends as would be necessary if these ends were inserted in the portions of each pair of headers which are adjacent; that is, in the faces 70 321 of the headers 10 and 11, as shown in Fig. 4. At the same time, the tubes are supported so that they may move in their own plane while the heater is in operation, and yet such supports will not interfere in any way with the removal or replacement of a 75 tube.

While I have shown my tubes in their preferred form, having a plurality of bends, it will be understood that for some purposes only one bend may be desirable. It will also be understood that, if desired, the tubes may be arranged singly instead of in clusters as illustrated. While, preferably, I arrange the bends so that the two legs of the tube are parallel, this is not necessary so long as the end portions of the legs extend generally 80 in the same direction. While I have illustrated a heater in which the headers are vertical, it will be understood that for many purposes the headers may be horizontal. 85

I claim:—

1. A fluid heater and its setting comprising a pair of parallel headers spaced apart and bent tubes connecting the headers, each tube lying in a plane at right-angles to the axes of the headers with the end portions of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portion of the tube, and the setting being arranged to permit such tube to be so withdrawn, the tubes being located entirely within the setting. 100

2. A fluid heater and its setting comprising a pair of parallel headers spaced apart and bent tubes connecting the headers, each tube having a plurality of bends and lying in a plane at right-angles to the axes of the headers with the end portions of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portions of the tubes, the tubes being located entirely within the setting, and the setting being arranged to permit the tubes to be withdrawn. 110 120 125 130

3. A fluid heater comprising a pair of parallel headers spaced apart and bent tubes connecting the headers, a setting for the heater, each tube having a plurality of bends and lying in a plane at right-angles to the axes of the headers with the end portions of the legs of the tube substantially parallel and extending generally in the same direction from the bent portion of each tube, each tube possessing sufficient flexibility to be withdrawn in its own plane between the headers without permanent deformation of the bent portion of the tube, the tubes being located entirely within the setting, and the setting being provided with an opening adjacent to said headers through which the bent tubes may be passed between said headers.

4. A fluid heater and its setting comprising a pair of parallel headers spaced apart and bent tubes connecting the headers, each tube lying in a plane at right angles to the axes of the headers with the end portions of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portion of the tube, and the setting being arranged to permit such tube to be so withdrawn, and supports for the tubes arranged to permit free motion thereof in their respective planes and the withdrawal of the tubes in said planes, the tubes being located entirely within the setting.

5. A fluid heater and its setting comprising a pair of parallel vertical headers spaced apart and bent tubes connecting the headers, each tube having a plurality of bends and lying in a horizontal plane with the end portion of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portion of the tube, and supports for the tubes arranged to permit free motion thereof in their respective planes and the withdrawal of the tubes in said planes, the tubes being located entirely within the setting.

6. A fluid heater and its setting comprising a pair of parallel headers located inside of and adjacent to said setting, unjoined bent tubes connecting said headers, the free ends of the tubes extending away from the wall of the setting adjacent to said headers, each tube lying in a plane at right-angles

to the axes of the headers with the end portions of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portion of the tube, the setting between said headers being provided with an opening through which the tubes connected to said headers may be inserted and removed and constituting the sole access for said tube, the tubes being located entirely within the setting.

7. A fluid heater and its setting comprising pairs of headers located adjacent to the walls of the setting, bent tubes connecting each pair of headers and extending inwardly towards each other, each tube lying in a plane at right-angles to the axes of the headers with the end portions of the legs of the tube extending in a substantially straight line from the bent portion thereof to the respective headers and connected to the headers, the space between the headers being sufficiently wide and the bent portion of each tube possessing sufficient flexibility to be withdrawn in its own plane between the headers without permanent deformation of the bent portion of the tube, the setting being provided between each pair of headers with openings through which the tubes connected to the associated headers may be inserted and withdrawn, and means for directing gases over the tubes connected to the pairs of headers.

8. A fluid heater comprising a plurality of parallel headers disposed in pairs placed side by side, bent tubes connecting each pair of headers and lying in planes at right-angles to the axes thereof, the normal width of the bent tubes being greater than the distance between said headers, each header being provided with transverse partitions and the partitions in each pair of headers being staggered in relation to each other, a flue for each pair of headers and its tubes, the flues being connected at their ends and one of the headers of each pair being connected at one end to a header of an adjacent pair, whereby fluid entering one of a pair of headers is directed back and forth between the pair of headers successively while moving longitudinally of the flue.

9. A fluid heater comprising a plurality of parallel headers disposed in pairs placed side by side, bent tubes connecting each pair of headers and lying in planes at right-angles to the axes thereof, each header being provided with transverse partitions and the partitions in each pair of headers being staggered in relation to each other, a flue for each pair of headers and its tubes, the flues

being connected at their ends and one of the headers of each pair being connected at one end to a header of an adjacent pair, whereby fluid entering one of a pair of headers is directed back and forth between a pair of headers successively while moving longitudinally of the flue, and the inlet and outlet gas connections to the flues and the inlet and outlet water connections to the headers being arranged so that the water flows through the headers and the tubes in a generally reverse direction to the flow of the gases over the tubes.

10. A fluid heater comprising a plurality of parallel headers disposed in pairs placed side by side, bent tubes connecting each pair of headers and lying in planes at right-angles to the axes thereof, the normal width of the bent tubes being greater than the distance between said headers, each header being provided with transverse partitions and the partitions in each pair of headers being staggered in relation to each other, a flue for each pair of headers and its tubes, the flues being connected at their ends and one of the headers of each pair being connected at one end to a header of an adjacent pair, whereby fluid entering one of a pair of headers is directed back and forth between the pair of headers successively while moving longitudinally of the flue, and the inlet and outlet gas connections to the flues and the inlet and outlet water connections to the headers being arranged so that the water flows through the headers and the tubes in a generally reverse direction to the flow of the gases over the tubes.

11. In combination, a fluid heater, a setting surrounding said heater, vertical headers located adjacent to a wall of said setting, bent tubes connecting said headers and extending away from said wall, each tube having a plurality of bends and lying in a horizontal plane with the end portions of the legs of a tube extending in a substantially straight line from the bent portions thereof to the respective headers and connected thereto, the space between the headers being sufficiently wide and the bent portion of each tube possessing sufficient flexibility to be withdrawn in its own plane between the headers without permanent deformation of the tubes, said wall of the setting being provided with removable portions through which the tubes may be withdrawn.

PAUL LOUIS GASTON ALBERT.
